UNITED STATES PATENT OFFICE.

JOHN M. OLIN, VICTOR L. DAVIS, AND JOHN B. SMITH, OF ALTON, ILLINOIS, ASSIGNEES
TO WESTERN CARTRIDGE COMPANY, OF EAST ALTON, ILLINOIS, A CORPORATION
OF DELAWARE

METHOD OF AND APPARATUS FOR FORMING DETONATOR IGNITER TERMINALS.

Original application filed December 30, 1922, Serial No. 609,954. Divided and this application filed November 5, 1925. Serial No. 67,186.

This invention relates to detonators, and more particularly to electrically ignited detonators. This application is a division of our application Serial Number 609,954, filed December 30, 1922.

As described in the parent application referred to, a plug of any suitable composition, such as sulphur and mica, is cast upon a pair of insulated wires, and the connections terminate a predetermined distance from each plug in order not only to provide a plug with a pair of connections, but also to provide terminals projecting from the plugs. The insulation on these terminals is stripped off so as to leave these terminals bare in order to receive the igniter wire or filament. The plug with the igniter wire attached thereto is then placed in a loaded detonator and sealed therein.

One of the objects of this invention is to provide a method and apparatus for so forming the ends of the igniter connections or terminals as to provide a seat for the filament or igniter wire.

Further objects will appear from the detail description taken in connection with the accompanying drawing, in which:

Figure 1 is a plan showing the terminal forming mechanism;

Figure 2 is a section on line 2-2, Figure 1;

Figure 3 is a section on line 3-3, Figure 2; and

Figure 4 is a perspective view, somewhat enlarged, showing the formed terminals.

Referring to the accompanying drawing, Figure 4 shows a plug 7 on the insulated igniter connection wires 6, and it will be noted that the ends 5 are not only stripped so as to be bare, but they are also notched or slit with the notches or slits running in a line in order to receive the igniter wire or filament.

An apparatus for performing the operation will now be described. It will, however, be understood that the apparatus is only illustrative of the method and that the method may be performed by simple manipulation apart from any specific mechanism.

Referring to Figures 1 to 4 inclusive, 63 is a block which is provided with a pair of passages 64 forming supporting guides for

the terminals 5, and with a recess 65 forming a support for the plug 7 on the connections 6. The bottom of the block is provided with a V-shaped groove 66 into which the terminals project with the apex of the groove passing medially through the alined terminals. Co-operating with this groove, which forms a die, is a V-shaped punch 67. Accordingly when the terminals projecting from beyond the plug are positioned as shown, operation of the punch will cause the same to cut alined V-shaped notches in these terminals as shown in Figure 4.

The block 63 is mounted on a frame 68 which has guides 69 for a cross-head 70, which carries the punch 67 and is connected by a link 71 with an operating arm 72 pivoted on the frame. Upon manipulation of the arm 72, therefore, the punch operates to notch the terminals, as shown in Figure 4.

It will, therefore, be seen that the invention accomplishes its objects. Means and mechanism are provided for forming the ends of the igniter connections to provide a seat for the filament or igniter wire and this seat is so formed that the filament may be readily placed therein a predetermined distance from the plug and secured therein in any suitable manner.

It is obvious that various changes may be made in details without departing from the spirit of this invention; it is, therefore, to be understood that this invention is not to be limited to the specific details shown and described.

Having thus described the invention, what is claimed is:

1. In the art of making detonators, the process comprising, forming the ends of a pair of igniter connections a predetermined distance from the plug thereon in a single operation in order to provide a filament seat.

2. In the art of making detonators, the process comprising, positioning the igniter connections by a plug thereon, and forming the ends of the connections while so positioned.

3. In the art of making detonators, the process comprising, alining the spaced ends of the igniter connections with the forming tool, and moving the tool past the alined ends.

4. In the art of making detonators, the process comprising, positioning the spaced ends of the igniter connections projecting from a plug thereon, in alinement, and forming the alined ends, while said ends are so positioned. 45
5. In the art of making detonators, the process comprising, positioning the spaced ends of the igniter connections projecting from a plug thereon, in alinement, and forming the alined ends a predetermined distance from the plug, while said ends are so positioned. 50
6. A machine for forming igniter connections, comprising, a support having a guide adapted to receive the connection, and a forming element adapted to operate on the connection. 55
7. A machine for forming igniter connections, comprising, a support having a guide adapted to receive the joined connections, and a forming element adapted to operate on the connections. 60
8. A machine for forming igniter connections, comprising, a support having a guide adapted to receive and aline a pair of igniter connections, and a forming element adapted to operate on the connections. 65
9. A machine for forming igniter connections, comprising, a support having a guide adapted to receive the connection and its attached plug, and a forming element adapted to operate on the connection. 70
10. A machine for forming igniter connections, comprising, a support having a guide adapted to receive the connection and its attached plug, and a forming element adapted to operate on the connection of a predetermined distance from the plug. 75
11. A machine for forming igniter connections, comprising, a support having a guide adapted to receive a pair of igniter connections and a plug thereon, and a forming element adapted to operate on the connections. 80
12. A machine for forming igniter connections, comprising, a support having a guide adapted to receive a pair of igniter connections and a plug thereon, and a forming element adapted to operate on the connections a predetermined distance from the plug. 85
13. A machine for forming igniter connections, comprising, a support having a guide adapted to receive a pair of igniter connections and a plug thereon in order to aline the terminals projecting from the plug, and a forming element adapted to operate on the terminals. 90
14. A machine for forming igniter connections, comprising, a support having a guide adapted to receive a pair of igniter connections and a plug thereon in order to aline the terminals projecting from the plug, and a forming element adapted to operate on the terminals a predetermined distance from the plug. 95
15. A machine for forming igniter connections, comprising, a die adapted to receive a plug and terminals projecting therefrom, and a cutter cooperating with said die. 100
16. A machine for forming igniter connections, comprising, a die adapted to receive a plug and terminals projecting therefrom, and a wedging cutter cooperating with said die adapted to groove the ends of the terminals. 105

In testimony whereof we affix our signatures this 20th day of August, 1925.

JOHN M. OLIN.

JOHN B. SMITH.

In testimony whereof I affix my signature this 14th day of Sept., 1925.

VICTOR L. DAVIS.

4. In the art of making detonators, the process comprising, positioning the spaced ends of the igniter connections projecting from a plug thereon, in alinement, and forming the alined ends, while said ends are so positioned. 45
5. In the art of making detonators, the process comprising, positioning the spaced ends of the igniter connections projecting from a plug thereon, in alinement, and forming the alined ends a predetermined distance from the plug, while said ends are so positioned. 50
6. A machine for forming igniter connections, comprising, a support having a guide adapted to receive the connection, and a forming element adapted to operate on the connection. 55
7. A machine for forming igniter connections, comprising, a support having a guide adapted to receive the joined connections, and a forming element adapted to operate on the connections. 60
8. A machine for forming igniter connections, comprising, a support having a guide adapted to receive and aline a pair of igniter connections, and a forming element adapted to operate on the connections. 65
9. A machine for forming igniter connections, comprising, a support having a guide adapted to receive the connection and its attached plug, and a forming element adapted to operate on the connection. 70
10. A machine for forming igniter connections, comprising, a support having a guide adapted to receive the connection and its attached plug, and a forming element adapted to operate on the connection of a predetermined distance from the plug. 75
11. A machine for forming igniter connections, comprising, a support having a guide adapted to receive a pair of igniter

connections and a plug thereon, and a forming element adapted to operate on the connections. 80

12. A machine for forming igniter connections, comprising, a support having a guide adapted to receive a pair of igniter connections and a plug thereon, and a forming element adapted to operate on the connections a predetermined distance from the plug. 85

13. A machine for forming igniter connections, comprising, a support having a guide adapted to receive a pair of igniter connections and a plug thereon in order to aline the terminals projecting from the plug, and a forming element adapted to operate on the terminals. 90

14. A machine for forming igniter connections, comprising, a support having a guide adapted to receive a pair of igniter connections and a plug thereon in order to aline the terminals projecting from the plug, and a forming element adapted to operate on the terminals a predetermined distance from the plug. 95

15. A machine for forming igniter connections, comprising, a die adapted to receive a plug and terminals projecting therefrom, and a cutter cooperating with said die. 100

16. A machine for forming igniter connections, comprising, a die adapted to receive a plug and terminals projecting therefrom, and a wedging cutter cooperating with said die adapted to groove the ends of the terminals. 105

In testimony whereof we affix our signatures this 20th day of August, 1925.

JOHN M. OLIN.

JOHN B. SMITH.

In testimony whereof I affix my signature this 14th day of Sept., 1925.

VICTOR L. DAVIS.

CERTIFICATE OF CORRECTION.

Granted May 10, 1927, to

Patent No. 1,627,860.

JOHN M. OLIN ET AL

It is hereby certified that error appears in the printed specification of the above numbered patent requiring correction as follows: Page 1, lines 91 and 92, claim 1 strike out the words "a pair of" and insert instead the article "the"; page 2, line 38, claim 10, strike out the word "of"; and that the said Letters Patent should be read with these corrections therein that the same may conform to the record of the case in the Patent Office.

Signed and sealed this 7th day of June, A. D. 1927.

M. J. Moore,
Acting Commissioner of Patents.
